UNITED STATES PATENT OFFICE.

WILLARD POPE PARSONS, OF HOOSICK FALLS, NEW YORK.

MECHANICAL MOVEMENT.

SPECIFICATION forming part of Letters Patent No. 595,968, dated December 21, 1897.

Application filed April 14, 1896. Serial No. 587,571. (No model.)

To all whom it may concern:

Be it known that I, WILLARD POPE PARSONS, of Hoosick Falls, in the county of Rensselaer and State of New York, have invented 5 a new and useful Improvement in Mechanical Movements and Incidental to it the Transmission of Power; and I do hereby declare the following to be a full, clear, and exact description of the same, reference being had to 10 the accompanying drawings, making a part of this specification, in which—

Figure 1 represents an elevation of my improvement in operative condition; Fig. 2, an elevation of yoke and gear. Fig. 3 is an elevation of the cylinder operating the same 15 with the sleeve broken off. Fig. 4 represents in elevation my device as applied to a hoisting apparatus. Fig. 5 represents a view in elevation taken on the line X X, Fig. 4. 20 Fig. 6 is a vertical cross-section of Fig. 4, taken on a plane passing through the axes of the gears. Fig. 7 is a sectional elevation of Fig. 6, taken on the line y y, Fig. 6.

The same letters in the several figures represent the same parts.

The nature and object of my invention are to provide a mechanism by which motion can be transmitted only by the application of power to a single piece and in no wise can 30 motion be transmitted from the driven to the driving side. This improvement is valuable as applied to hoists and various machines and vehicles in which the driving power is suddenly cut off and the mechanism is required 35 to remain in a state of rest, notwithstanding power is still exerted on the driven side.

In order to enable others skilled in the art to make and use my invention, I will proceed to describe the same in reference to the drawings.

A represents a shaft to be driven carrying a bevel-gear B, keyed thereto, as shown at C. Turning freely on shaft A is a cylinder H, which is formed on two axes, one coincident 45 with the axis of shaft A, the other inclined thereto. The inclined portion of this cylinder H is of larger diameter than the other part and forms a bearing for a second gear-wheel D. The two gear-wheels B and D are 50 furnished with teeth to mesh together. The wheel D is supported in what I term a "ring-yoke" F, the wheel D being fitted with two

trunnions or hubs E opposite each other and which fit into and are held in boxes on the ring-yoke. The ring-yoke is supported by 55 two trunnions or hubs G opposite each other and on a line at right angles to the line of the trunnions E. Trunnions G work in bearings or boxes permanently fixed to the main frame of the hoist, vehicle, or machine, as 60 may be required, which form a support for the device. To the sleeve of cylinder H—that is, the part where the axis is parallel to shaft A—is applied the driving power through pulley, hand-wheel, armature, or any other approved method. I have shown a hand-wheel 65 in Figs. 4, 6, and 7.

The bevel-gear D being mounted on the inclined cylinder, as described, and so supported by the trunnions E, turning in the 70 ring-yoke, and the ring-yoke being supported by the trunnions G on the frame, when power is applied to the cylinder H to rotate it about the axis of shaft A the gear D will take a wabbling instead of a rotary motion and 75 some of its teeth will be in mesh with the teeth on wheel B, and consecutive wabbling movements of the wheel D will engage its teeth one after the other with teeth in wheel B. The wheel D has a greater number of 80 teeth than wheel B. Consequently the wheel B will have rotated when all the teeth in D have been engaged a distance corresponding to the excess of teeth in D and turn the shaft A with its load.

In Figs. 4 and 6 I have shown in a hoisting-machine a sleeve K, fastened to shaft A, over which a chain can be passed to raise the weight to be hoisted.

I do not deem it necessary to describe any 90 of the other forms of the application of this mechanical movement for transmitting power. While it is particularly adapted, as shown in the drawings, to a hoisting-machine, it is evident that modifications in construction of different well-known mechanical devices can be used to apply the same to other purposes for communicating motion and force.

When motion of wheel D is arrested by throwing off the belt, stopping electric current or other device applied to cylinder H, and force is still left to turn shaft A—for instance, when a weight being raised is suspended—this force cannot result in turning

shaft A, and the mechanism will all remain in a state of rest, as the force, while it tends to rotate wheel B, and therefore wheel D, in a reverse direction, will be resisted by the 5 gimbal-joint form of connection of wheel B.

Having thus fully described my invention, what I claim therein as new, and desire to secure by Letters Patent, is—

10 The combination of a shaft, two gears thereon differing as to their number of teeth and meshing together, a cylinder upon which

one of said gears is mounted and which forms an inclined bearing for said gear, said cylinder having a bearing upon the axis of the other gear, and a yoke or controlling device 15 whose axis of motion intersects the axis of the cylinder at a common point, substantially as and for the purpose described.

WILLARD POPE PARSONS.
